ELECTRON BEAM DEFLECTING MEANS

Franklin P. Kenyon, New York, N. Y.

Application March 16, 1939, Serial No. 262,078

7 Claims. (Cl. 250—157)

My invention relates to cathode-ray tube beam deflecting arrangements and more particularly relates to novel electromagnetic beam deflecting means for such tubes.

5 The invention is useful for cathode-ray tube applications in general. However, the present disclosure is made with specific application to television scanning systems, without intending to limit the scope thereof. The invention relates 10 to electromagnetic means for deflecting a cathode-ray beam along two coordinate planes, generally mutually perpendicular. In television the cathode-ray beam is deflected at line frequency to traverse a square or rectangular field on the 15 screen at a definite number of frames per second. Saw-tooth wave forms are generally used for framing, or the lower frequency, as well as for the higher, or line, frequency. The fundamental line frequency is generally of the order of 13,000 20 cycles. For efficient action of the saw-tooth wave form it is necessary to include the harmonics up to 100,000 cycles or more in the line deflecting section.

In accordance with the present invention I 25 contemplate a compact electromagnetic cathode-ray beam deflecting system which is highly efficient and operable over a wider frequency range and with relatively lower voltages than prior structures. The arrangement of the magnetic 30 deflecting system is to entail a minimum inductance and intercoupling between the sets of deflecting coils for effective utilization of all the upper harmonics of the saw-tooth signal wave form. The framing or low frequency magnetic 35 portion of the system is provided with a laminated iron magnetic path for high deflectional sensitivity. Large pole faces, equal to the diameter of the neck of the cathode-ray tube, are provided for uniform deflection fields to substantially minimize defocusing and pincushion 40 effects.

An important feature of my present invention is the provision of a highly efficient air core magnetic system for the line or high frequency deflecting section. I have found that a serious defect with prior magnetic deflecting systems resides in the provision of an iron core in the effective magnetic construction of the high frequency section. In accordance with my present invention, I eliminate iron in the magnetic path of this section to substantially increase the deflectional efficiency of the coils. Power loss in the iron at the high frequencies becomes serious, and elimination of this iron path results in many advantages. A resultant advantage is a decreased

5 inductance, which provides an efficient transmission for the complex saw-tooth wave harmonic frequencies of the high frequency coil scanning arrangement. Furthermore, a small effective axial length of the high frequency coil 10 system is effective in producing the requisite beam deflection sensitivity. The elimination of the prior common magnetic yoke for both deflecting coil sets permits decoupling of these sections and substantially reduces any interference effects between them.

The air-core high frequency coil set is electrically magnetically and mechanically balanced to substantially minimize intercoupling with the 15 low frequency or other circuit. This coil set is closely mechanically related and arranged with the iron core low frequency coil set to constitute a compact mutually independent magnetic deflecting system. In the preferred embodiment, 20 the effective portion of the high frequency coils is juxtaposed with the effective pole faces of the low frequency coil system as will be hereinafter described in more detail.

Resultant features of the arrangement of the 25 present invention are the substantial elimination of pincushion effect on the cathode ray tube screen in the simultaneous deflection of the beam with the low and high frequency coil systems, and the elimination of beam defocusing 30 effects.

It is accordingly an object of my present invention to provide a novel magnetic deflecting system for the beam of a cathode ray tube.

Another object of the invention is to provide 35 a dual magnetic deflecting system efficiently operable over a wide frequency band extending from low frequencies up to radio frequencies.

Still another object of the present invention is to provide a magnetic deflecting system having 40 an efficient iron core low frequency path in combination with a highly efficient air core high frequency path.

A further object of the present invention is to provide a novel dual magnetic beam deflection system, mutually electrically independent and with substantially negligible magnetic intercoupling between the two sections.

Still a further object of the present invention is to provide a novel compact highly efficient cathode ray beam magnetic deflecting system simultaneously operable in two directions with a wide frequency range of operation.

These and further objects of the present invention will become apparent in the following 55

description taken in connection with the drawings, in which:

Figure 1 is a perspective illustration of the magnetic deflecting system arranged on a cathode ray tube.

Figure 2 is an elevational view of the magnetic deflecting device with a cover removed.

Figure 3 is a horizontal cross-sectional view through the deflecting device taken along the line 3-3 of Figure 2.

Figure 4 is a vertical cross-sectional view through the magnetic deflecting device taken along the line 4-4 of Figure 3.

Figure 5 is an enlarged perspective illustration of the high frequency deflecting coil section of the device.

Figure 6 is a diagrammatic representation of the magnetic lines of force emanating from the deflecting sections of the magnetic device of the 20 invention.

The magnetic deflecting device generally indicated by 10 is shown in operative correlation upon the neck 12 of a cathode ray tube 11. Cathode ray tube 11 is of the conventional type having an electron "gun" which generates the electron beam 14 impinging upon the fluorescent screen 15 at the opposite end of the tube. Sources of potential (not shown) are applied to the tube in the conventional manner.

30 In television systems, the cathode ray beam 14 is deflected in a regular manner to traverse a rectangular region such as 16 on the fluorescent screen 15. The number of frames or complete traversals for the image 16 is termed the framing frequency and corresponds to the number of images projected per second. The number of lines constituting each frame 16 determines the "line" frequency. The fundamental line frequency in present systems ranges in the order of 40 13,000 cycles per second.

As is well known in the art, saw tooth wave forms for the framing and line signals are used to obtain the uniform rectangular pattern. As indicated schematically at 17, the frame signal 45 generator is connected by leads 18 to posts 19 of the deflecting device for the low frequency or framing magnetic section thereof.

The higher line signal frequency generator is indicated at 20 and is connected by leads 21 to 50 posts 22 of the device. The simultaneous action of the framing and line signal generators through the corresponding magnetic portions of the deflecting device 10 motivates electron beam 14 in a manner to produce the rectangular image 16 55 as will be understood by those skilled in the art.

The magnetic deflection device of my present invention is a compact unit relatively inexpensive to manufacture. The width of the unit along the neck 12 of the cathode ray tube is made relatively short without sacrificing deflectional sensitivity of the system. I incorporate the frame or low frequency magnetic section together with the line or frequency section while maintaining both sections highly efficient and without electrical or magnetic interference between them.

The low frequency section comprises an iron magnetic core path to produce a uniform transverse field across the cathode ray tube. The high 70 frequency section is arranged to have a substantially all air magnetic path for maximum efficiency and minimum inductance. The saw-tooth wave form of generators 17 and 20 are accordingly faithfully imparted upon both magnetic sections for producing the proper uniform mag-

netic fields within the cathode ray tube for obtaining the rectangular deflection pattern 16. The correlation of both magnetic systems is such as to materially diminish the possibilities of defocusing or pincushion effects in the cathode ray 5 tube operation.

Figures 2, 3 and 4 are respectively elevational and sectional views through a preferred form of the magnetic deflecting device 10. The physical embodiment is essentially a transformer unit 10 having an additional air core magnetic coil section for the high frequency deflections. As seen in the drawings, unit 10 is constructed within a non-magnetic shell 25 fitted on both ends by composition or Bakelite cover plates 26 and 27. The low frequency or framing section of the device comprises the laminated magnetic iron section 28 and two symmetrically disposed windings 30 on opposite legs of the magnetic structure. Core 28 may be constructed of silicon steel 20 stampings having a thickness of the order of .014 inch.

The assembly of laminations 28 is similar to that of a transformer, and in a preferred embodiment is a closed core unit having a central spacing or opening to accommodate the neck 12 of the cathode ray tube.

Vertical angle irons 31-31 are welded or otherwise secured along the rear edges of casing 25 and are arranged for securing laminations 28 by bolts 32. Horizontal cross-bars 33-33 are arranged at the front side of the laminated structure for clamping the laminations into a rigid structure in cooperation with bolts 32. The low frequency coils 30 are prewound and inserted upon the outer legs of the core structure in a manner similar to the assembly of transformers.

A plurality of tap leads 35 are made in each of the coils 30 for individual connection to the terminal posts 19 of the unit. By suitable interconnection of frame signal generator leads 18 with posts 19, a wide range of impedance matching between the low frequency magnetic system and generator is feasible.

Low frequency coils 30 are connected for producing a common additive magnetic flux extending between pole faces 36, 36. Fiber spacers 37 are inserted between the sides of coils 30 and the inner core regions to prevent movement of the coils upon the core. The vertical height of pole faces 36 is preferably made at least equal to the diameter of the cathode ray tube neck 12 which fits into the cylindrical central fiber tube 38 of the device. The frame signal currents flowing through coils 30 which generates a magnetic field across pole face 36, 36. The magnetic field is substantially uniform in intensity throughout the region corresponding to the movement of the cathode ray beam therewithin, as will be explained in further detail in connection with Figure 6. The horizontal disposition of the magnetic field causes the electron beam to sweep vertically up and back in accordance with the framing frequency.

An important feature of my present invention resides in the provision of a substantially air cored coil system for the high frequency of line signal deflections. The high frequency coils are shown at 40. They are constructed by originally winding the coils in a rectangular form with a rather flat hank. Coils 40 are curved about tube 38 to substantially 180° of it. The longitudinal section of coils 40 are parallel to the axis of the cathode ray tube and are ar-

ranged symmetrically with respect to the low frequency coil system 30. The arcuate ends of coils 40 are twisted around for a complete 360° turn to substantially eliminate defocusing effects 5 of these turns as will be described hereinafter.

A physical advantage of the twisting of the arcuate portions of coils 40 is that the coils are fitted between pole faces 36 with a squeeze fit and folded over edges prevent axial dislodgement of the walls as will be further shown.

The current flow through the curved sections of coils 40 which lie in two planes perpendicular to the axis of the tube is such that their magnetic effects normally cancel. However, the 15 folding over of these portions further reduces effective action of these coil sections upon the cathode ray beam. The magnetic fields about these portions lie outside of the path of movement of the electron beam in the neck of the 20 tube, practically eliminating defocusing and pincushion effects by the magnetic system. Both coils 40 of this section are electrically connected to produce a common magnetic deflecting field within the cathode ray tube. The coils 40 are 25 shown connected in series by leads 41, 41 connected to terminal posts 22, and bridging lead 42 between the coils.

Figure 5 is an enlarged perspective view of the high frequency coil section 40-40 with the co- 30 acting low frequency magnetic pole faces 36-36, shown in dotted. The coils 40 are originally wound flat with many layers to keep its distributed capacity relatively small. Each coil section 40 is then bent around the central tube 38 to subtend about 180° thereof. The longitudinal legs 45 of coils 40 accordingly are arcuate and lie flat against the central tube 38. The windings of legs 40 are all parallel to the tube and produce a magnetic field within the cylindrical 40 neck 12 of the cathode ray tube, in a vertical direction, for the orientation of the coils as shown in Figure 5. The arrows at sections of coils 40 generally indicate the effective direction of current flow therethrough to produce the desired magnetic effects.

The transverse legs 46 of the coils are arcuate about the central tube. It will be noted that the current flow through the turns of coil sections 46 is such as to mutually cancel magnetic 50 effects between them. However, an important added precaution for insuring elimination of defocusing and pincushion effects by these coil sections is provided as follows:

The originally flat transverse coil sections 46 are rolled back on themselves for one complete revolution of 360°. The bank of turns is tied by threads 47 to keep them together as a unitary structure. The folding over of the transverse turns 46 reduces the path for the leakage flux 60 so that the non-linear field therefrom is concentrated in an area closer to the coil itself. This area is substantially removed from the path traversed by the electron beam in the central cylindrical portion.

65 The folding over of transverse turns 46 produces bulged portions 50 where they meet the flat smooth longitudinal leg portions 45. The length of legs 45 is made equal to the width of the pole faces 36. It will be understood, however, that the length of the legs 45 may be varied depending upon the degree of desired 70 sensitivity of the high frequency deflecting coils. Thus, for example, for greater sensitivity of the high frequency coils, the length of the legs 45 would be greater than the pole faces and for

lesser sensitivity would be shorter. The transverse legs 46 accordingly constitute ridges for the coil units 40. The central flat section 45 of the coils 40 are juxtaposed against the faces of poles 36. The outside diameter of the coil assembly 40, 40 is made equal to the distance between the pole faces 36-36. A closely integrated structure accordingly results. The coils assembly is fitted between the pole faces 36 and maintained in rigid position by the close fitting 10 nature of the assembly.

The structure is economical to construct and relatively simple to manufacture in mass production. The complete device is relatively small in bulk and light in weight. The magnetic efficiency of the system is very high and extends from the very low frequencies required for framing to the very high frequencies including the upper harmonics of the television line signal waves. The iron path is for the low frequency 20 section and imparts a very good beam deflection sensitivity for this section with a relatively short longitudinal dimension. Thus the length of pole faces 36 parallel to the tube axis may be of the order of one inch. With nominal signal intensity of energization from the framing frequency generator 17, such construction has been found to produce very satisfactory results.

The high frequency coil section 40, 40 has its effective magnetic action along the flat longitudinal leg portions 45 which are juxtaposed against the pole faces 36. Legs 45 are as close to the electron beam position as is feasible. The effective air core opening in the central section of coils 40 is designed to give a uniform flux 35 pattern inside the portion of the tube over which the beam traverses. This opening can be found by calculation or experimentation in accordance with well defined procedure known in the art.

The effective air core path for the magnetic 40 system of the high frequency coil section 40, in conjunction with its relatively short over all length, (less than two inches), results in a highly efficient magnetic action therefor with low losses and low inductance when compared with prior 45 equivalent structures. I have found that this coil section effectively functions with frequencies extending up into the radio frequency spectrum. This simplified design is accordingly capable of handling very high line frequencies of the sharp 50 saw tooth wave form required for television use. Its construction is also capable of other applications than television particularly where the required frequency band is very wide.

I have further discovered that by constructing 55 the casing 25 of a non-magnetic material that I prevent thereby any magnetic losses that may otherwise occur by reason of a tendency of the magnetic lines of force flowing in a by-pass around such a magnetic casing.

Figure 6 is an enlarged cross-sectional view transverse to the axis of neck 12 of the cathode ray tube with the adjacent sections of the magnetic deflecting device positioned thereon. On Figure 6 is schematically drawn magnetic lines 65 of force emanating from the two magnetic sections of the device to illustrate how they cooperate to act upon the cathode ray beam within the tube for producing the rectangular television scanning pattern 16 referred to hereinabove with 70 a minimum of beam defocusing and pincushion effects. The rectangle 60 shown with dashed lines centrally within the neck 12 of the cathode ray tube represents the boundaries of the movement of the cathode ray beam of the tube during 75

the production of the rectangular image 16 upon fluorescent screen 15 shown in Figure 1. For negligible defocusing action and little pincushion effect it is essential that the magnetic fields extending within the region 60 be of uniform intensity and parallel with respect to the size of the boundaries thereof. As seen, the horizontal dash-dot lines extending between pole faces 36 constitute the resultant magnetic action of the 10 low frequency coil system 38-38 operating upon the closed core 28.

The pole faces 36 are extended and in a practical case are made about equal to the diameter of the neck 12 of the cathode ray tube. The 15 magnetic lines 80 extending intermediate of the outer edges of the pole faces 36 are truly horizontal and of uniform intensity. The outer magnetic lines 81 between pole faces 36 are curved as will be evident to those skilled in the art. 20 However, the essential portion of the magnetic path, namely that lying within boundary 60, is truly horizontal and of uniform intensity as required.

The horizontal legs 45 of coil section 40-40 25 produces magnetic lines 90 adjacent thereto and curved thereabout, gradually merging to form a common vertical magnetic array 91 intermediate thereof. Current flowing through the right and left leg portions are similar, producing the additive magnetic effect centrally of the tube. The 30 disposition of the magnetic fields 91 within the rectangular region 90 is truly vertical in the illustrated example and of uniform intensity. Any unevenness or curving of the magnetic lines 35 occurs outside of this boundary and is immaterial since it does not affect the operation of the beam deflection system.

It is thus seen that in the described example the compact magnetic system produces two sets 40 of fields mutually perpendicular and uniform throughout the central beam deflection region 60. It is to be understood that the orientation of coil set 40, 40 with respect to pole faces 36, 36 45 may differ from that shown to constitute a dual magnetic deflection system not mutually perpendicular in action. It is to be understood that the magnetic deflection device of the present invention is applicable to other uses than television. Thus it may be applied to deflecting a 50 cathode ray tube beam in radio direction finders or blind landing systems, laboratory oscillograph applications, etc. The two respective deflection circuits are electrically, mechanically and magnetically balanced to greatly minimize the effects 55 of intercoupling between the high and low frequency circuits. The balanced nature of the coil systems materially decreases the possibility of interference from extraneous electrical action.

Although I have illustrated a particular embodiment of the invention, it is to be understood that modifications which fall within the broader spirit and scope of the invention are feasible, and accordingly, I do not intend to be limited except as set forth in the following claims.

65 I claim:

1. A device for magnetically deflecting the electron beam of a cathode ray tube comprising a closed laminated core structure having centrally opposed flat pole faces at least as wide as the 70 neck of the cathode ray tube and of the order of one inch in thickness; a pair of windings individually and symmetrically wound on said core structure, said windings being interconnected to constitute with said core structure the lower frequency beam deflection section of the device 75

with relatively small inductance; a pair of air-cored layer flat-wound coils bent around to subtend substantially 360 degrees of arc with side portions parallel to the longitudinal axis of the device, the arced sections of said coils being 5 twisted about themselves for a complete revolution of substantially 360 degrees to localize magnetic flux thereabout and to prevent beam defocusing thereby.

2. A device for magnetically deflecting the electron beam of a cathode ray tube comprising a closed laminated core structure having opposed flat pole faces at least as wide as the neck of the cathode ray tube and of the order of one inch in thickness; winding on said core structure, said winding constituting with said core structure the lower frequency beam deflection section of the device with relatively small inductance; a pair of air-cored layer flat-wound coils bent around to subtend substantially 360 degrees of arc with side portions parallel to the longitudinal axis of the device, the arced sections of said coils being twisted about themselves for a complete revolution of substantially 360 degrees to localize magnetic flux thereabout 10 and to prevent beam defocusing thereby, 15 and being symmetrically disposed to minimize intercoupling effects therefor, the air-core section of said coils lying outside the region of said iron pole faces to minimize inductance and losses 20 for the coils for efficient utilization of a relatively wide frequency band by the coils for uniform deflection of the beam thereby. 25

3. A device for magnetically deflecting the electron beam of a cathode ray tube comprising a laminated core structure having opposed pole faces; a winding on said core structure; said winding constituting with said core structure the lower frequency beam deflection section of the device; a hollow cylinder fitted between said 40 pole faces; a pair of air-cored flat-wound coils bent around said cylinder to subtend substantially 360 degrees of arc thereabout with side portions parallel to the longitudinal axis of the device, the arced sections of said coils being 45 twisted about themselves for a complete revolution of substantially 360 degrees to localize magnetic flux thereabout, the flat longitudinal side portions of said coils being juxtaposed between said cylinder and pole faces with the 50 twisted over sections of the coils extending adjacent the outer sides of said pole faces to constitute a mutually supporting and mechanically stable structure for the device.

4. A device for magnetically deflecting the electron beam of a cathode ray tube comprising a laminated core structure having opposed pole faces; a pair of windings individually and symmetrically wound on opposite legs of said core structure, said windings being interconnected to 60 constitute with said core structure the lower frequency beam deflection section of the device with relatively small inductance; a hollow cylinder fitted between said pole faces; a pair of air-cored flat-wound coils bent around said cylinder to subtend substantially 360 degrees of arc thereabout with side portions parallel to the longitudinal axis of the device, the arced sections of said coils being 65 twisted about themselves for a complete revolution of substantially 360 degrees to localize magnetic flux thereabout and to prevent beam defocusing thereby and being symmetrically disposed to minimize intercoupling effects therefor, the flat longitudinal side portions of said coils being juxtaposed between said cylinder and pole 70 75

faces with the twisted over sections of the coils extending adjacent the outer sides of said pole faces to constitute a mutually supporting and mechanically stable structure for the device, the 5 air-core section of said coils lying outside the region of said iron pole faces to minimize inductance and losses for the coils and permit efficient utilization of a relatively wide frequency band by the coils for uniform deflection of the beam 10 thereby.

10. A device for magnetically deflecting the electron beam of a cathode ray tube comprising a closed laminated core structure having centrally opposed flat pole faces at least as wide as the 15 neck of the cathode ray tube and of the order of one inch in thickness; a pair of windings individually and symmetrically wound on opposite legs of said core structure, said windings being interconnected to constitute with said core structure the lower frequency beam deflection section 20 of the device with relatively small inductance; a pair of air-cored layer flat-wound coils bent arcund to subtend substantially 360 degrees of arc with side portions parallel to the longitudinal 25 axis of the device, the arced sections of said coils being twisted about themselves for a complete revolution of substantially 360 degrees to localize magnetic flux thereabout and to prevent beam defocusing thereby, and being symmetrically disposed to minimize intercoupling effects therefor, the air-core section of said coils lying outside the 30 region of said iron pole faces to minimize inductance and losses for the coils for efficient utilization of a relatively wide frequency band by the coils 35 for uniform deflection of the beam thereby.

6. A device for magnetically deflecting the electron beam of a cathode ray tube comprising a laminated core structure having centrally opposed pole faces; a pair of windings individually wound on opposite legs of said core structure; said windings being interconnected to constitute with said core structure the lower frequency beam deflection section of the device; a hollow cylinder 40 fitted between said pole face; a pair of air-cored

flat-wound coils bent around said cylinder to subtend substantially 360 degrees of arc thereabout with side portions parallel to the longitudinal axis of the device, the arced sections of said coils being twisted about themselves for a complete 5 revolution of substantially 360 degrees to localize magnetic flux thereabout, the flat longitudinal side portions of said coils being juxtaposed between said cylinder and pole faces with the twisted over sections of the coils extending adjacent the outer sides of said pole faces to constitute a mutually supporting and mechanically stable structure for the device.

7. A device for magnetically deflecting the electron beam of a cathode ray tube comprising a closed laminated core structure having centrally opposed flat pole faces at least as wide as the neck of the cathode ray tube and of the order of one inch in thickness; a pair of windings individually and symmetrically wound on opposite legs of said core structure, said windings being interconnected to constitute with said core structure the lower frequency beam deflection section of the device with relatively small inductance; a hollow cylinder fitted between said pole faces; a pair of 20 air-cored coils bent around said cylinder to subtend substantially 360 degrees of arc thereabout with side portions parallel to the longitudinal axis of the device, the arced sections of said coils being twisted about themselves for a complete revolution 25 to localize magnetic flux thereabout, and the flat longitudinal side portions of said coils being juxtaposed between said cylinder and pole faces with the twisted over sections of the coils extending adjacent the outer sides of said pole faces to 30 constitute a mechanically stable structure for the device, the air-core section of said coils lying outside the region of said iron pole faces to minimize inductance and losses for the coils and permit efficient utilization of a relatively wide frequency 40 band by the coils for uniform deflection of the beam thereby.

FRANKLIN P. KENYON.
